T. BENSON

CORD TIGHTENER FOR AWNING OPERATORS

Filed Oct. 8, 1920

Patented Oct. 30, 1923.

1,472,742

UNITED STATES PATENT OFFICE.

THOMAS BENSON, OF WASHINGTON, DISTRICT OF COLUMBIA.

CORD TIGHTENER FOR AWNING OPERATORS.

Application filed October 8, 1920. Serial No. 415,581.

To all whom it may concern:

Be it known that I, THOMAS BENSON, a citizen of the United States, residing at Washington, in the District of Columbia, have invented new and useful Improvements in Cord Tighteners for Awning Operators, of which the following is a specification.

The object of this invention is to provide a cord tightener for awning operators where-
10 by the awning may be raised and lowered from the inside of the building and without the necessity of the window or the like being opened for the entry of the elements.

With this and other objects in view as
15 will be more specifically pointed out in the following specification and claims, reference will be had to the accompanying drawing forming a part of this specification and wherein like numerals of reference designate
20 corresponding parts throughout the several views, in which:—

Fig. 1, is an elevation of a fragment of a window with awning lowered viewed from the inside of the building;

25 Fig. 2 is a vertical transverse sectional view thereof;

Fig. 3 is a front elevation view of the cord tightener;

30 Fig. 4 is a side elevation view of Fig. 3;

Fig. 5 is a horizontal sectional view taken through Fig. 4 on the line 5—5;

Fig. 6 is a front elevation of a fragment of the window viewed from the inside of the building, and

35 Fig. 7 is a longitudinal vertical sectional view through the cord guide.

Referring to the drawing, reference numeral 1 denotes the wall of a building, in which is set the usual window frame 2, having the usual guide strips 3, 4 and 5. Between the guide strips 3 and 4 slides the lower window sash 6, while between the guide strips 4 and 5 slides the upper sash 7. The strip 3 extends down the sides of the sash and across the top thereof, and in a like manner extend the other guide strips 4 and 5. The awning 8 is attached in the usual manner as by fastenings 9 to the building and has the usual operating cord 10 passing through the usual screw eyes 11. Instead of the operating cord extending down the outside wall of the building and there fastened, the same passes from said eyes 11 through a tubular guide 12, thence down the inner face of the window framing where it is adjustably attached to a cord tightener

14 which is slidably adjustably mounted on a ratchet rod 15, secured at its opposite ends to the window framing.

The guide strip sections 3 at the top and one side of the window framing are cut out for the accommodation of the cord guide member 12, as illustrated in Fig. 6, and similarly are the guide strips 4 and 5 cut away. This permits the cord guide member to be placed in the extreme corner of the window frame and there secured by screws 16 the heads of which are permitted to pass through the outer wall of the cord guide due to the enlarged openings 17, and said openings 17 receive the screw driver in placing these screws. In Fig. 6, it will further be noted that the upper sash 7 (and the lower sash also if desired) is notched or cut out as at 18 in one corner for the accommodation of the cord guide member, and by this construction, when the upper sash is fully raised and between the guide strips 4 and 5 at the top, no opening is presented for entrance of wind, except the small immaterial opening 80 through the cord guide. To promote free and easy passage of the awning operating cord 10 through the cord guide member 12, said member is equipped at its front end with a roller 20, in the plane of the lower wall of the guide member and journaled between two downwardly extending ears struck from the body of said cord guide member. Also, at its rear end, other rollers 22 are provided in the plane of the side 90 walls of the cord guide member and journaled between extensions 23 of said cord guide member.

The cord tightener 14 comprises two sections 24, 25 secured together by transverse 95 bolts 26. Upon one of the sections, in the drawing, section 24, is mounted a cleat 27 to which the awning operating cord 10 is secured; and in the lower end of one of these sections, shown in the drawing as section 100 24, is inserted a screw eye 28 which serves as a handle for adjusting the cord tightener on the rod 15. At intervals, the rod 15 has ratchet teeth 29, to hold the cord tightener in adjusted position, through the medium of 105 a pawl 30 pivoted to the other said section 25 of the cord tightener. This pawl operates in a recess 31 and is normally engaged with said rod 15 due to being under the tension of a spring 32 attached to said 110 pawl and to a screw or pin 33 and located within a recess 34. When the two sections

24 and 25 are secured together, the inner wall of member 24 closes the open side of the recesses 31 and 34. Embedded within the sections 24 and 25 at both the upper and lower ends are guide fingers 33, the projecting ends of which are L-shaped and facing each other to embrace the ratchet rod 15.

In operation, when it is desired to raise the awning, the cord tightener is pulled 10 down the ratchet rod 15, by releasing the pawl 30 and inserting a finger in the screw eye 28, or the pawl need not be released since it will ride over the ratchet teeth of the rod and when the awning has been fully raised 15 will enter behind one of the ratchet teeth and retain the awning in raised position. To lower the awning, the pawl 30 is disengaged from the ratchet teeth 29 and the cord tightener permitted to ride up the ratchet rod until 20 the awning is fully lowered. By regulating the position of the cord tightener along the ratchet rod with respect to the position of the awning before attaching the cord to the cleat 27, engagement of the pawl 25 with the ratchet teeth at the proper time is insured.

Of course it will be understood that it is the intention to alter and modify the structural details within the scope of the claims, 30 and to make such other minor changes as will improve and perfect the invention.

What is claimed as new and desired to be secured by Letters Patent is:—

1. A cord tightener, comprising a ratchet rod and a slider mounted thereon, said slider comprising two matching sections, each provided with guide fingers embracing said rod, one of said sections being provided with a pawl for engagement with said rod, and a cleat on one of said sections for the attachment of the cord.

2. A cord tightener, comprising a ratchet rod and a slider mounted thereon, said slider comprising two matching sections, each section being provided with an L-shaped finger and the fingers closing about said rod when the sections are matched, one of said sections being provided with a recess, a spring pressed pawl mounted pivotally within said recess, the other of said sections closing said recess when the sections are matched, a cleat on one of said sections for the attachment of the cord, and a screw eye inserted into the lower end of one of said sections as a handle.

In testimony whereof I have hereunto set my hand in presence of two subscribing witnesses.

THOMAS BENSON.

Witnesses:

JOHN RUNNELS,

CHARLES SMITH.
